CLAIM

The ornamental design for a golf tee, as shown and described.

DESCRIPTION

FIG. 1 is a bottom perspective view of a golf tee showing our new design;

FIG. 2 is a side elevational view thereof; and,

FIG. 3 is a top perspective view thereof.

The broken lines in FIG. 3 are included for the purpose of illustrating a portion of the golf tee that forms no part of the claimed design. The appearance within the rectangular area shown in FIGS. 1 and 2 likewise forms no part of the claimed design.
